UNITED STATES PATENT OFFICE

2,525,494

CIRCUIT INTERRUPTER

Leon R. Ludwig, Wilkinsburg, Benjamin P. Baker, Turtle Creek, and Winthrop M. Leeds, Wilkinsburg, Pa., assignors to Westinghouse Electric Corporation, a corporation of Pennsylvania

Original application November 11, 1942, Serial No. 465,244. Divided and this application December 22, 1945, Serial No. 636,941

4 Claims. (Cl. 200—150)

1

This invention relates to circuit interrupters, and, more particularly, to arc extinguishing structures therefor. This application is a division of our copending application, Serial No. 465,244, filed November 11, 1942, now United States Patent 2,406,469, issued August 27, 1946.

More specifically our invention relates to a novel structure for effecting the very rapid extinction of electric arcs drawn in circuit interrupters. It is particularly applicable to the interruption of high voltage arcs, such as those drawn in a 287 kv. circuit, and will effect their interruption in less than one cycle. Our invention is, however, not limited in its application only to high voltage circuits. It is also applicable on low voltage circuits, but merely for purposes of illustration it is described in the specification in a preferred embodiment as used on a high voltage circuit.

Extensive experimental investigation has clearly demonstrated that a rapid lowering of the dielectric strength of an arc extinguishing fluid, such as oil, occurs after it impinges upon the arc stream. It is therefore desirable to eliminate such contaminated fluid as quickly as possible, and to subject the arc stream to the action of fresh fluid of high dielectric strength. It is one of the objects of our invention to provide an arc extinguishing structure which makes full use of this fact.

Another object is to provide an improved arc extinguishing structure which will direct a plurality of spaced jets of arc extinguishing fluid at the arc and will permit the venting of such jets at a number of spaced intermediate points along the arc.

Another object of our invention is to provide improved differential piston means associated with the moving contact structure to effect the rapid extinction of low current arcs.

A further object of our invention is to provide an improved circuit interrupter employing a novel type of differential piston which cooperates with novel arc extinguishing passage structures disposed adjacent to the separating contacts.

A still further object is to provide a circuit interrupter of the type set forth in the preceding paragraph in which the parts are disposed in symmetrical arrangement to relieve or minimize unbalanced forces acting upon the operating mechanism.

Further objects and advantages will readily become apparent upon a reading of the following description taken in conjunction with the drawings, in which:

2

Figure 1 is a side elevational view in cross section of a circuit interrupter embodying our invention and shown in the closed-circuit position;

Fig. 2 is a side elevational view in cross section taken on the line II—II of Fig. 1, but showing the interrupter in the partially open circuit position; and

Fig. 3 is a plan view in cross section taken along the line III—III of Fig. 1.

Referring to the drawing, and more particularly to Fig. 1 thereof, it will be observed that we have provided an interrupting unit having a resiliently mounted relatively stationary contact 118 cooperating with a rod-shaped movable contact 119. A metallic tubular guide 120 is provided to guide the movement of the relatively stationary contact 118. A line terminal connection 121 is made at the upper end of the guide 120.

A tubular insulating casing 122 is provided, within which reciprocally moves a piston 123 preferably made of insulating material. A compression spring 124 biases the piston 123 downwardly as viewed in Fig. 1. Movable with the piston 123 is a tubular insulating member 125 at the upper end of which is threadedly secured a metallic plate or ring 126 which slides over the guide member 120. Threadedly secured to the lower end of the guide member 120 is an insulating arcing chamber 127 formed in this instance from a single piece of insulating material. A plurality of inlet passages or fluid channels, in this instance four, are provided being designated by the reference numerals 128. A plurality of vent passages 129, in this instance four, are provided leading from shallow openings or pockets 147, the disposition of which are more clearly shown in Fig. 3. Between each inlet passage 128 and each vent passage 129 is an annular oil pocket or recess 130 which serves to retain fresh oil adjacent the arc 131 which is drawn during the opening operation when the movable contact 119 is withdrawn downward away from the relatively stationary contact 118. Not only do the oil pockets or recesses 130 retain fresh oil or other arc extinguishing fluid adjacent to the arc 131, but also they provide a corrugated arc passage 145 which prevents the arc 131 from contacting insulation surfaces during its elongation.

The arcing chamber or extinguishing means 127 has openings formed therein to provide fluid conducting passages 148. These interconnect to form the fluid channels or inlet passages 128.

Disposed at the lower end of the piston 123 and encircling the movable contact 119 is a washer

132 which during the opening operation serves to close an annular aperture 133 in the lower portion of the piston 123.

Secured rigidly to the movable contact 119 is a sleeve 134 having a perforated disk 135 integrally formed therewith, the purpose for which will appear more fully hereinafter. A stop ring 136 is provided at the lower end of the tubular insulating casing 122 to limit the downward travel of the piston 123.

The operation of the interrupter will now be described. In operation, the tubular insulating casing 122 is completely immersed in a suitable arc extinguishing fluid, such as oil. When it is desired to open the circuit passing through the interrupter, the movable contact 119 is drawn downward. The relatively stationary contact 118 follows the initial downward movement of the movable contact 119 until the washer 137 strikes the top of the guide 120. At this point, the movable contact 119 separates from the relatively stationary contact 118 to draw an arc 131, more clearly shown in Fig. 2. Meanwhile, the compression spring 124 has forced the piston 123 downward within the casing 122 to move with it the tubular insulating member 125 and the metallic ring 126. The oil disposed in the region 138 is compressed and forced to flow downward into the inlet passages 128, as indicated by the arrows 139. The oil forced to flow into the inlet passages 128 contacts the arc 131 and flows thereafter through the oil pockets 130 to be vented through the vent passages 129, as designated by the arrows 140 in Fig. 2.

During the interruption of low currents, the compression spring 124 provides the necessary biasing force to move the piston 123 downward and hence displacing the oil in the region 138 so as to cause it to flow into the inlet passages 128. During the interruption of high currents, the piston 123 and the ring 126 cooperate to constitute a differential piston. Thus, the surface area of the ring 126 is less than the surface area of the piston 123. Therefore, the net force tending to move the piston 123 downward will cooperate with the compression spring 124 to cause, on the interruption of high currents, increased fluid flow from the region 138 into the inlet passages 128 to contact the arc 131. It will be apparent that the arc 131 acts on the piston 123 through the vent passages 129, and that the arc 131 acts on the metallic ring 126 through the inlet passages 128.

The resulting movement of the oil causes rapid extinction of the arc 131. It will, therefore, be apparent that in this embodiment of our invention we have devised a structure which utilizes the arcing pressure in conjunction with a differential piston to assist arc interruption during the interruption of high currents.

Referring particularly to Fig. 3, it will be noticed that the inlet passages 128 communicate with an enlarged annular region or shallow opening or pocket 141 which insures that the flow directed into the interrupting arc 131 will be radially thereof about the periphery of the arc stream 131. It will be noted that the portion of the arc passage 145 between a pocket 141 and a pocket 147 may be termed a recessed orifice portion 149 as indicated on the drawing, the recessing arising by virtue of the presence of the pockets 130. The passage structure is partly described and claimed in our copending application filed December 22, 1945, Serial Number 636,940,

now United States Patent 2,467,760, issued April 19, 1949, to us, and assigned to the assignee of the instant invention.

During the opening operation, the sleeve 134 surrounding the movable contact 119 and movable therewith permits the washer 132 to close the annular aperture 133 in the piston 123. During the closing of the interrupter, the sleeve 134 strikes the washer 132 to raise the latter and permit fluid to flow out through the annular aperture 133 to permit quick closing of the interrupter.

Although we have illustrated a specific embodiment it will be clearly understood that the same was merely for the purpose of illustration and that changes and modifications may be made therein by those skilled in the art without departing from the spirit and scope of the appended claims.

20 We claim as our invention:

1. A circuit interrupter including means for establishing an arc, arc extinguishing means of insulating material forming an arc passage for the arc closely confining the arc along a major portion of its length, said arc extinguishing means defining at least two shallow openings along the arc passage larger than the opening of the arc passage to thereby provide a plurality of pockets at spaced intervals along the arc passage, said arc extinguishing means having other openings therein on at least opposite sides of said arc passage to provide fluid conducting passages, the arc extinguishing means being slotted between the fluid conducting passages to provide fluid channels to at least one of said pockets, said arc extinguishing means being slotted from at least another of the pockets to the opposed external surfaces of the arc extinguishing means to provide venting passages from said other pockets, and the walls of the arc passage having at least one recess between adjacent pockets to provide fresh fluid along the arc passage and also to break up the insulation surfaces to minimize the possibility of voltage breakdown axially along the arc passage.

2. A circuit interrupter including means for establishing an arc, arc extinguishing means of insulating material for defining a substantially enclosed arc passage of insulating material closely confining the arc along a major portion of its length, said arc extinguishing means defining a recessed orifice portion within the arc passage, the arc extinguishing means defining a pair of diametrically positioned inlet passages on one level so that an incoming flow of fluid may pass through the inlet passages inwardly toward the arc substantially transversely thereto on opposite sides thereof, said arc extinguishing means forming a venting passage therein positioned on the opposite side of the recessed orifice portion permitting relatively restricted venting of the fluid.

3. A circuit interrupter including a substantially enclosed interrupting unit, a movable differential piston member having larger and smaller surface areas exposed to the arcing pressure, the larger surface area of the movable differential piston member constituting one outer movable wall of the interrupting unit, an opening provided in said movable outer wall of the interrupting unit, means for establishing arcing within the interrupting unit including a rod-shaped movable contact movable along the opening, means biasing the differential piston to

move in a direction to force liquid toward the arc to extinguish the same, and means associated with the movable contact for picking up the differential piston on the closing stroke of the interrupter to charge the same against the biasing force exerted by the biasing means.

4. A circuit interrupter including a substantially enclosed interrupting unit, a movable differential piston member having larger and smaller surface areas exposed to the arcing pressure, the larger surface area of the movable differential piston member constituting one outer movable wall of the interrupting unit, an opening provided in said movable outer wall of the interrupting unit, means for establishing arcing within the interrupting unit including a rod-shaped movable contact movable along the opening, means biasing the differential piston to move in a direction to force liquid toward the arc to extinguish the same, valve means associated with the opening, and means associated with the

10 5

movable contact for picking up the differential piston on the closing stroke of the interrupter to charge the same against the biasing force exerted by the biasing means and opening the valve
